UNITED STATES PATENT OFFICE.

ANTONIO D. FRASCOLA, OF EL RENO, OKLAHOMA.

SHOE FASTENER.

1,269,274.

Specification of Letters Patent. Patented June 11, 1918.

Application filed March 31, 1917. Serial No. 158,927.

To all whom it may concern:

Be it known that I, ANTONIO D. FRASCOLA, a citizen of the United States, residing at El Reno, in the county of Canadian and State of Oklahoma, have invented certain new and useful Improvements in Shoe-Fasteners, of which the following is a specification, reference being had to the accompanying drawings.

- 10 This invention relates to certain improvements in shoe fasteners and has relation more particularly to a device of this general character of a pull type; and it is an object of the invention to provide a novel and improved shoe fastener wherein the lace or string engages the flaps or margins of the lace opening in a plane substantially parallel thereto instead of being disposed transversely therethrough.
- 15 20 The invention also has for an object to provide a fastener of this general character wherein a supplemental lace coacts with the main lace and which is engageable therewith when the shoe is loosened and which serves to afford means whereby the requisite pull may be imparted to the main string or lace for tightening the shoe.

The invention consists in the details of construction and in the combination and arrangement of the several parts of my improved shoe fastener whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be better understood, I will now proceed to describe the same with reference to the accompanying drawings, wherein—

Figure 1 is a view in side elevation of a shoe having a fastening means applied thereto constructed in accordance with an embodiment of my invention;

Fig. 2 is an enlarged fragmentary sectional view taken substantially on the line 2—2 of Fig. 1; with the lace or string omitted; and

Fig. 3 is a fragmentary view in elevation showing the supplemental lace or string and the adjacent end portions of the main lace or string with which the same is adapted to coact.

While I disclose in Fig. 1 a shoe wherein the lace opening is in a side of the upper, I wish it to be understood that I do not desire to limit myself to any particular part of the upper in which said opening is arranged. 60

As herein disclosed, each of the flaps or marginal portions 1 of the lace opening of the shoe have disposed longitudinally thereof a supplemental flap 2 suitably secured along its inner longitudinal margin to the shoe top by the stitching 3 or other suitable means. The outer or free longitudinal margins of the flaps 1 and 2 are maintained in predetermined spaced relation through the medium of the interposed studs 4 arranged 65 in predetermined longitudinal spaced relation.

As is particularly illustrated in Fig. 2, each of the studs 4 is provided adjacent its opposite ends with the annular flanges 5 which engage the inner faces of the flaps 1 and 2 and engage with the outer end portions of the stud 4 and overlying the outer faces of the flaps 1 and 2 are the eyelets 6 which coact with the annular flanges 5 to 80 clamp the stud 4 in applied position. The stud 4 is preferably hollow whereby it will be perceived that by expanding the end portions of said stud 4, the eyelets 6 may be maintained in requisite clamping position. 85

L denotes a main lace or string which is disposed around the studs 4 arranged at opposite sides of the lace opening so that said lace or string may readily serve to contract the lace opening in the top of the shoe. 90 When the top is in open adjustment as indicated in Fig. 1, it is to be noted that the free extremities of the lace or string L will expand below the upper edge of the top.

In order that the lace or string L may be 95 readily drawn around the upper studs 4, I employ the supplemental lace or string 7 of a gage less than the gage of the lace or string L and preferably formed of gut. One end of said supplemental lace or string 7 is provided with an eyelet 8 adapted to be detachably engaged with the catch 9 carried by an end of the main lace or string L, while the opposite end of the supplemental lace or string 7 is provided with the catch 10 adapted 100 to be engaged with the eyelet 11 carried by the second end of the main lace or string L. The coacting eyes 8 and 11 and catches 9 and 10 result in a positive connection of the extremities of the lace L and the sup-

plemental lace or string 7 so that the pull imposed upon the string 7 is transmitted to the lace L.

The supplemental lace or string 7 is adapted to be engaged with the ends of the main lace or string L before the lace opening is pulled open so that the supplemental lace or string will readily pass around the studs 4. When it is desired to lace the shoe 10 it is only necessary to impose a pull upon the supplemental lace or string 7 to cause the main lace or string L to properly engage all of the studs. After the shoe has been laced in accordance with the desires of the wearer, 15 the supplemental lace or string 7 is disconnected therefrom and the free end portions of the lace or string L tied in a conventional manner.

From the foregoing description, it is 20 thought to be obvious that a shoe fastener constructed in accordance with my invention is of an extremely simple and comparatively inexpensive nature and is particularly adapted for use by reason of the convenience and 25 facility with which it may be assembled, and

it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed. 30

I claim:

As an article of manufacture, a shoe string comprising two separable sections, one of said sections being of a gage less than the second section, a catch secured to an extremity of each of the sections, an eyelet secured to the opposite extremity of each of the sections, the catch and eyelet of one section interlocking the eye and catch of the second section. 40

In testimony whereof I hereunto affix my 45 signature in the presence of two witnesses.

ANTONIO D. FRASCOLA.

Witnesses:

A. A. PITNEY,
NELL POOLE.
